UNITED STATES PATENT OFFICE

HERBERT L. THOMPSON, OF ELGIN, AND ELI WILDERSON, OF CHICAGO, ILLINOIS, ASSIGNORS TO ADDRESSOGRAPH COMPANY, OF WILMINGTON, DELAWARE, A CORPORATION OF DELAWARE

PRINTING MACHINE

Application filed July 28, 1938. Serial No. 298,036.

This invention relates to printing machines for printing in successive operations from a single body form and successively changing address forms selected for printing in accordance with a predetermined classification.

The primary object of the invention is to provide a printing machine of simple, novel and compact design and construction for printing consecutively from a single body form and from successively changing address forms, or for printing consecutively from the body form and without an address form.

Another object is to provide novel means at one side of the body form for feeding address forms one at a time from the bottom of a stack in a magazine, for moving each form to be printed laterally into printing position and back after the printing operation into feeding position, and for continuing the feeding movement to discharge position.

Another object of the invention is to deposit and hold the paper in printing position during the printing movement of the carriage, to give the printed sheet an initial discharge movement in the direction of the return movement of the carriage, and then to accelerate the discharge movement of the paper in a downward direction.

Other objects of the invention are to provide simple and novel means for raising and lowering the address forms as they are moved into and out of printing position so as to clear the ribbon and to avoid obstructing or interfering with the travel of the carriage in either direction; for adjusting the platen to the work and to obtain clear and uniform printing impressions; to lower the platen into operative position at the end of the return movement of the carriage and to raise the platen out of operative position at the end of the forward movement of the carriage; to raise the platen out of operative position at the beginning of the forward travel of the carriage if a sheet is not in position to be fed to printing position; to feed the ink ribbon at each operation of the machine; and to deliver the printed sheets in a pile in a drawer provided to receive them in the frame of the machine below the carriage.

Another important feature of the invention

is to provide new and novel selective means for selecting predetermined address forms to be printed and to prevent address forms not selected for printing from being carried to printing position.

And further objects of the invention are to provide means adapted to be operated by a printing device not to be printed for preventing movement of the carriage, and to provide manually operated means for releasing the carriage and for removing the address form which was not selected for printing.

In the accompanying drawings illustrating a selected embodiment of the invention, the views are as follows:

Fig. 1 is a top plan view of the printing machine.

Fig. 2 is a side elevation.

Fig. 3 is a transverse sectional view on the line 3—3 of Fig. 1.

Fig. 4 is a longitudinal sectional view on the line 4—4 of Fig. 1.

Fig. 5 is a detail longitudinal sectional view on the line 5—5 of Fig. 1.

Fig. 6 is a side elevation at the right side of the printing device magazine.

Fig. 7 is a detail perspective view of the magazine and printing device carrying mechanism.

Fig. 8 is a sectional view similar to that shown in Fig. 5, but with the carriage in printing position.

Fig. 9 is a detail perspective view of the printing device feed mechanism.

Fig. 9—A is a detail perspective view of a portion of Fig. 8.

Fig. 10 is a rear view of the machine.

Fig. 11 is a detail perspective view of the ribbon supporting frame.

Fig. 12 is a transverse sectional view through the ribbon feeding means.

Fig. 13 is a longitudinal sectional view on the line 13—13 of Fig. 1.

Fig. 14 is a longitudinal sectional view on the line 14—14 of Fig. 1.

Fig. 14—A is an enlarged sectional view of a portion of Fig. 14.

Fig. 15 is a sectional plan view on the line 15—15 of Fig. 2, with all the parts of the machine in normal or initial printing posi-

- tion, certain parts being broken away for clearness.
- Fig. 16 is a sectional plan view on the line 16—16 of Fig. 2 with the printing device magazine omitted.
- Fig. 17 is a sectional view through the carriage on the line 17—17 of Fig. 1 showing the platen in printing position.
- Fig. 18 is a view similar to Fig. 17 with the carriage in advanced position.
- Fig. 19 is a longitudinal sectional view through the carriage on the line 19—19 of Fig. 17.
- Fig. 19—A is an enlarged sectional view of a portion of Fig. 19.
- Fig. 20 is a sectional plan view of the carriage on the line 20—20 of Fig. 19.
- Fig. 21 is a transverse sectional view through the carriage on the line 21—21 of Fig. 19.
- Fig. 22 is a transverse sectional view on line 22—22 of Fig. 19.
- Fig. 23 is a sectional view on the line 23—23 of Fig. 14.
- Fig. 24 is a sectional view on the line 24—24 of Fig. 14.
- Fig. 25 is a detail perspective view of the printing device supporting block which is employed when the machine is operating consecutively.
- Fig. 26—28 inclusive are diagrammatic views showing the machine in various printing positions.
- Referring to the drawings, 1 designates a main frame having depending longitudinal side bars 2, 2 and a carriage 3 having a lower part 4 and an upper part or housing 5, is mounted for reciprocal movement on the frame. Ball bearings 6, 6 Fig. 19 of the type disclosed in co-pending application Serial No. 243,868, filed December 31, 1927, are interposed between the side bars and the frame to facilitate the movement of the carriage. It is desirable to provide locking means which will prevent any reverse movement of the carriage before it has completed its full stroke, and to this end I provide a roller 7, Figs. 4 and 5, which travels on the edge 8 of the main frame, Fig. 19, and cooperates with the cam faces 9, 9 on a block 10 inserted in a recess 11 in the carriage, and also with spaced recesses 12, 12 in the edge 8 of the main frame. The roller 7 is confined between the edge 8 of the frame and the cam faces 9, 9 and the walls of the recess 11 so that it will always be retained in place between the carriage and the frame. The recesses are provided at the end of the travel of the carriage in each direction to permit reverse movement of the carriage. While the carriage is traveling between the ends of its movements in either direction the roller is riding on the edge 8 of the frame and is carried along by the carriage; the cam faces 9, 9 are disposed to wedge the roller between the carriage and the frame at any position of the roller between the recesses 12, 12 and this wedging will lock the carriage so that it cannot be moved in reverse during its forward movement or during its return movement.
- A cross shaft 13 is mounted in the lower part 4 of the carriage and a roller 14 mounted on said shaft engages a groove 15 in the cam lever 16, which is pivoted to the frame at 17, Figs. 15 and 16. During reciprocation of the carriage the roller 14 engages the cam lever groove 15 and reciprocates the cam lever 16 transversely. An upstanding finger or pin 18 is fixed to the forward end of the cam lever and it engages a slot 19, Fig. 15, in the sliding carrier plate 20 so that during reciprocation of the carriage the cam lever 16 will cause transverse reciprocation of this carrier plate.
- A frame 21, Fig. 3 for the feeding mechanism is secured to the main frame and supports the magazine 22 which carries a stack of printing devices 23 bearing the address or other forms, Figs. 5 to 10 inclusive. A feed bar 24, more clearly shown in Fig. 9, is slidably mounted on the feed frame 21, and a feed bar handle 25 carrying a lug 26 is pivotally mounted on the end of the feed bar as clearly shown in Fig. 9. A lug 27, Fig. 15 projects outwardly from the carriage and engages the lug 26 on the handle so that during reciprocatory movement of the carriage the lug 27 will move the feed bar 24 rearwardly. A tape 28, Fig. 6 connected to the feed bar and to the spring barrel 29 returns the feed bar to normal or initial position during forward movement of the carriage. A spring bumper 30 is arranged at the end of the feed frame 21 to limit the return movement of the feed bar 24, Fig. 6. A pair of arms 31, Fig. 9, are connected to the forward end of the feed bar 24 and extend rearwardly to the magazine 22. These arms are adapted to engage the front edge of the lowermost printing device 23 in the magazine and push said device from beneath the stack and to a position opposite its printing position. A plate 32, Fig. 15, is fixed to the carrier plate 20 and a printing device carrier block 33 is detachably mounted thereon. A sliding bed 34, Figs. 15 and 24, is provided with a plurality of recesses 35, Fig. 24, which receive the pins 36 fixed in the main frame. The sliding bed 34 is stepped up at 38 to provide a shoulder 39 against which the plate 32 strikes during inward movement of the carrier plate 20. As plate 20 continues to move to the left, Fig. 15, plate 32 will engage shoulder 39 and carry the bed 34 with it and cause said bed to ride up on the pins 36 and slide to printing position, Fig. 24 and supporting the carrier and bed block 33 in proper relation to the bed 37 and the address printing device 23 in printing position and in proper relative position

to the body form 37'. An arm 40, Fig. 15, fixed to the bed 34 carries an upstanding pin 41, which is adapted to be received in an aperture 42 arranged in the bar 43 fixed to the plate 20 to properly register the bed 34 and to return it to normal position during return movement of the carrier plate 20. A suitable bumper or stop 44 is fixed to the main frame to limit the return movement of the sliding bed 34. The carrier plate 20 is supported by a plurality of rollers 45 fixed to a part of the main frame Figs. 14, 15. A yoke 46 fixed to the feed bar 24 and connected to the pusher arms 31 by the rods 47, has a rocker shaft 48 mounted therein Figs. 9, 15. A pair of feed dogs 49 are fixed on the shaft 48 to engage the forward edge of a printing device 23 in the position to which the arms 31 push the bottom printing device in the stack. A slide bar 50, having slots 51, is slidably mounted on screws 52 which are screwed to the supporting frame 21 for the feed mechanism. The bar 50 is thus capable of longitudinal movement guided by the guide slots 51 and the screws 52. An arm 53 carrying a pin 54 is fixed to the end of the shaft 48 and, during movement to the left, Fig. 9, of shaft 48, rides under the bar 55 fastened to the stop of the slide bar 50, thereby swinging the dogs 49 down to grasp the forward edge of the printing device during sliding movement of the feed bar 24, to the left in Fig. 9. Upon reaching the end of said movement or travel of the feed bar 24, the pin 54 will ride under the flexible finger 57, which is fixed to the bar 55 and which springs down into the path of the pin 54 as said pin passes beyond the finger. Upon return movement, to the right, Fig. 9, of the feed bar 24, the pin 54 will ride up on the flexible finger 57 and turn the shaft 48 to restore the dogs 49 to their raised position and to clear any printing device in pushed position, Fig. 26. A finger 58 is fastened to the yoke 46 and engages one of the dogs 49 to limit their upward movement Fig. 6. A bar 59 is fixed to the yoke 46 and alternately engages at the ends of its stroke the pins 60, 60' which are fixed to the slide bar 50, Fig. 9. During reciprocatory movement of the feed bar 24 the bar 59 alternately strikes the pins 60, 60' causing longitudinal and vertical movement of the slide bar 50 due to the guide slots 51. A spring 61, fastened to the slide bar and to a part of the feed frame, acts to yieldingly hold the slide bar 50 in normal position Fig. 9, in relation to guide slots 51 and screws 52. The movement of the slide bar 50 is for the purpose of lowering and raising the selector bar yoke 62.

This yoke 62 is pivotally mounted on the stud 63 fixed to the feed frame 21 and carries the selector pin bar 64 Fig. 8. A pin 65 is fixed to one arm of the yoke 62 and operates in a slot 66 in the slide bar 50, and when said slide bar moves toward the left in Fig. 9 said pin moves into the clearance provided in said slot and the spring 62' is free to move the yoke 62 downwardly and therefore move the selector bar into a position to perform a selection. When the slide bar 50 moves in the opposite direction the pin 65 engages the lower formed edge of the slot 66 and the pin 65 and therefore the yoke 62 and bar 64 are positively forced upwardly.

A rod 67, Figs. 5 and 6, pivotally mounted on the stud 63 has a block 68 formed thereon against which the set screw 69, threaded in the yoke 62, bears to move the rod 67 during vertical movement of the selector pin bar 64. A bell crank 70 pivoted to the feed frame at 70' is provided with a pin 71 at one end thereof which engages a slot 72 in the rod 67 so that during movement of the selector pin bar and the rod 67, the end 73 of the bell crank will move laterally, Fig. 9-A. The end 73 of the bell crank 70 is slotted at 74 to receive the pin 75 on the transverse bolt 76 which is slidably mounted in a channel shaped member 77 fastened to the bottom of the feed frame at 78, Figs. 6, 8 and 9. When the selector pin bar moves vertically, the rod 67 operates the bell crank 70 by means of the slot 72 and the pin 71 to slide the bolt 76 transversely in the member 77. When the yoke 62 swings down, the bolt 76 will project inwardly in the path of the carriage and when the selector pin bar has reached the limit of its downward travel the bolt 76 will recede slightly to permit the carriage to pass. The inward and outward movement of this bolt is operated by the pin 71 operating in the slot 72. When the pin is in either the upper or lower straight portion of the slot 72 the bolt 76 is free from engagement with the carriage but when the pin 71 is in the curved intermediate portion 72' of the slot the bolt 76 engages a part of the carriage and prevents movement thereof. A suitable spring 79 connects the rod 67 with the yoke 62, Fig. 6, to return the rod to normal or initial position after it has been operated by the yoke 62.

A packer 80 is pivoted to the feed frame and has an arm 81 projecting therefrom which extends through an opening 82 in the side of the feed frame Figs. 5, 8. A beveled lug 83 is fixed to the feed bar 24 so that during forward movement of the carriage the lug 83 will strike the arm 81 and move the packer forwardly, to the right, Fig. 8 and pack the printing devices 23 against the slideable weight 84 in the compartment 85 beneath the feed frame. A spring 80' is connected to the packer 80 to return it to initial position. A chute 86 is suitably connected to the feed frame, Figs. 5 and 8, through which the printing devices pass to the bottom of the compartment 85 as indicated by the directional arrow in Fig. 5.

In practice a stack of printing devices is arranged in the magazine 22 and the car-

riage is set in normal or initial position, as shown diagrammatically in Fig. 26. The carriage is pushed forward through printing position as shown diagrammatically in Fig. 27. Then the carriage is moved rearwardly as shown diagrammatically in Fig. 28 to initial position, Fig. 26. During its rearward movement the lug 27 on the carriage will engage the lug 26 on the feed bar handle 25 and move the feed bar 24 rearwardly to carry a printing device to discharge position. As the feed bar moves rearwardly, the arms 31, 31 will also move rearwardly and push the bottom printing device 23 in the magazine rearwardly until it comes to proper position on the block 33 carried by the carrier 20, 32. Upon forward movement of the carriage the cam lever 16 will move the plate 20 to carry the block 33 to proper position on the carrier bed 34, which then raises the carrier block 33, bearing the printing device, to printing position. Upon the next rearward stroke of the carriage, the cam lever 16 will return the block 33 from printing position 25 to pushed position on the feed frame so that when the lug 27 strikes the lug 26 to move the feed bar 24, the dogs 49 will engage the printing device which has just been printed and carry it along to the discharge chute 86 30 as the pusher arms 31 engage the next succeeding printing device to push it into position on the block 33.

It is desirable that certain printing devices should be selected for printing and that those not to be printed should be prevented from attaining printing position in the machine. In this adaptation of the invention tabs 87 are arranged on those devices which are not to be printed. When a printing device bearing a tab is passing from the magazine, a selector pin 88 Figs. 5, 6 and 8, on the selector pin bar 64 will strike the tab as the bar descends, and the bell crank pin 71 will be held in the curved portion 72' of 40 the slot 72, and the bolt 76 will project inwardly into the path of the carriage and prevent further movement thereof, so that this particular printing device will not be carried to printing position. The feed bar handle 25, which is pivoted to the end of the feed bar 24, is moved laterally by hand to free the lug 26 from the lug 27 on the carriage, and this handle is then pulled rearwardly to operate the feed bar 24, whereby 45 the dogs 49 will engage the tabbed printing device and carry it to the chute through which it will fall into the compartment 85. A spring 89 engages the end of the feed bar handle and the feed bar to return the handle 50 after operation to its normal position. This spring is relatively stiff but sufficiently yieldable to permit lateral movement of the handle to disengage the lug 26 from the lug 27 to permit manual operation of the feed bar.

5 A skeleton ribbon frame 90, Figs. 11, 12

and 14, fits around the bed 37 and supports a pair of removable spindles 91 which carry the ink ribbon 92 stretched across the body form. Clamping heads 93, 93', having recesses 94 are fixed to pins 95, 95' which are 70 slidably mounted in diagonally opposite corners of the ribbon frame. A spring 96 is arranged between each head 93 and the ribbon frame to normally urge the heads inwardly. The heads 93' have ratchet teeth 75 97 thereon and are provided with recesses 98 to receive the ribbon spindles. Projections 99 are arranged in slots 100 in the spindles and are received in notches 101 in the heads 93'. The ribbon is guided on cross bars 102 80 at the ends of the ribbon frame.

A sliding bolt 103, Fig. 13 arranged in a boss 104 in the front end of the main frame carries a pin 105 which is adapted to be engaged by a lug 106 on the bottom of the carriage during its forward movement. An arm 107 is pivoted to the rear end of the sliding bolt and extends upwardly therefrom, and a spring 108 is attached to the rear end of the arm to normally hold the arm 90 up so that when the carriage moves the bolt forwardly, the pin 109 on the arm will engage and operate one of the ratchets 97 for rotating the ribbon spool which is acting as a take-up spool. The spring 108 also serves 95 to return the bolt to normal position when the carriage proceeds on its rearward movement. The forward end of the bolt is recessed at 110, Fig. 13, to receive a lug or finger 111 to limit the forward and rearward 100 movement of the bolt. During each forward stroke of the carriage, the bolt 103 will cause the ratchet to turn slightly to wind some of the ribbon from one spindle onto the other 105 spindle. When, however, one spindle is nearly wound and the other nearly unwound, the entire frame 90 may be turned end for end on the printing form, and inasmuch as the ratchets are located diagonally opposite, the 110 spool from which the ribbon is being unwound will now be in position to do the winding.

A plate 112 is pivoted to the frame at 113, Figs. 1, 14, and 14-A, and it carries a clip 114 made of spring metal and having knobs 115, which extend through holes 116 in the mask 119. The cross bars 102 of the ribbon frame are provided with recesses 118 to receive the knobs 115. A mask 119 having printing openings 120 is provided with apertures 116 through which the knobs 115 project to hold the mask on the plate 112. In the form shown this mask allows certain portions of the body form and the address form to be printed and prevents the platen 125 from coming in contact with the ribbon at the end of the printing stroke.

A sheet supply holder is mounted on the carriage and it comprises a frame 122, Figs. 3, 13 and 14, having a pair of downwardly 130

and forwardly extending slotted arms 123 to detachably engage the transverse rods 124 and 125. The rod 125 is threaded on one end and carries a square nut 126, which is arranged between one of the arms 123, and another adjacent and integral arm 123' Fig. 3. A knurled knob 127 is fixed to the end of the rod 125 to rotate the same. During rotation of the rod 125 the squared nut 126 is translated along the threaded portion of the rod and moves the supply frame 122 longitudinally, so that sheets 128 may be properly positioned laterally relative to the body form. A rod 129 is pivotally mounted in the supply frame 122, Fig. 14 and it carries a baffle 130. A pair of guides 131 are connected to the supply frame to side register the sheets. One of the guides 131 is provided with a projection 132 which projects through a slot 133 in the frame and is guided by the bars 134 to permit side movement of the guide to accommodate sheets of various widths. A set screw 135 is secured to the projection 132 and a thumb nut 136 maintains this guide in adjusted position. A rod 137 is detachably mounted in the supply frame, and a rack 138 is slidably mounted on the rod. A set screw 139 is provided in the lower end of the rack 138 to move the rack vertically on the rod 137 to accommodate sheets of various lengths. The rod 137 is provided with a longitudinal groove 140 Fig. 3, which receives the set screw 139 so that the rack 138 is always maintained in proper parallel position relative to the frame 122. A slot 141 Figs. 17 and 18 is provided at the top of the housing or upper part 5 of the carriage near its forward end in which the guides 142 and 143 are mounted and through which the sheet is fed to printing position.

A pair of oppositely disposed transverse ribs 144, Figs. 17, 18 and 20, are arranged on each end of the upper portion 5 of the carriage and receive bearing blocks 145 Figs. 19 and 20 in which the shaft 146 of the platen 147 is revolvably mounted. Screws 148 Fig. 19 extend through the housing 5 of the carriage and threadedly engage the blocks 145. Springs 149 confined between the heads 150 of the set screws 148, and the projections 151 normally hold the platen in receded position. Cam members 152 are arranged at the outer end of the platen shaft 146 and are adapted to be operated to maintain the platen in impression position Fig. 17 or in receded position Fig. 18. Thumb nuts 153 are threaded in the carriage housing 5 and receive the threaded members 154 which have a lower pitch than the thumb nuts 153. The threaded members 154 carry rollers 155 in slots 155' to engage the cam members 152 which extend into the slots and are guided by the walls thereof, Fig. 19. It will be noted that the thumb nuts 153 have a relatively high pitch outside thread and a relatively low pitch inside thread so that a fine adjustment of the threaded members 154 may be easily obtained by a relatively rough adjustment of the thumb nuts, and in this way the platen can be easily adjusted to secure 70 the desired impression effect.

A sheet feed roller 156 Figs. 17, 18 and 20 is pivotally mounted in the yoke 157 which is pivoted at 157' at each side of the housing 5. A pinion 158 is fixed to the feed roller shaft 159 and engages a pinion 160 Fig. 21 which meshes with the rack 161 fastened to the main frame. A pair of blocks 162 Figs. 17, 18 and 21 have relatively large slots 163 Figs. 17 and 18 which receive the feed roller shaft 159 and engages a pinion 160 Fig. 21 for the feed roller 155. Set screws 164 extend through the housing 5 and engage the blocks 162 for adjusting the feed roller relative to the platen 147. Springs 165 normally urge the blocks 162 inward so that the feed roller shaft normally attains the position in the slot 163 shown in Fig. 18. A relatively heavy spring 166 connected to a pin 167 on the yoke 157 and to a pin 167' on the housing 5, normally urges the yoke toward the platen with the feed roller positioned to engage the platen. The feed roller 156 is rotated during reciprocation of the carriage by the pinion 158 operated by the pinion 160 95 which engages rack 161.

The platen is lowered to printing position at the end of the rearward stroke of the carriage and receded or raised from printing position at the end of the forward stroke so that when the carriage returns rearwardly the platen will not come in contact with the ribbon or the body form. The platen is operated by means of the cams 152, and an arm 168 fixed to one of the cams 152 operates to move the cams 152 to operate the platen. A pin 169 on the arm 168 engages the shoulder 170' on the arm 170 at the end of the rearward stroke of the carriage and operates the arm 168 to bring the platen to impression position relative to the body form and then print a sheet during the forward movement of the carriage. When the carriage reaches the end of its forward stroke the pin 169 will strike a lug 180 on the main frame 1 and operate the arm 168 and move the cams and raise the platen from printing position.

A sheet is fed between the platen 147 and the feed roller 156 during forward or printing stroke of the carriage. The feed roller is in contact with the platen during the forward or printing stroke of the carriage and is retracted from the platen during the rearward stroke of the carriage to provide a space between the feed roller and the platen so that a sheet may be readily inserted in the sheet feed slot 141. An arm 174, Figs. 17, 18, rigid with the yoke 157 is adapted to be operated to move the feed roller towards or away from the platen. A tripper 175 pivoted to the yoke 130

at 176 holds the yoke in operating or retracted position relative to the platen, Figs. 19, 19—A and 21. The tripper 175 has a notch 177' at its upper end which is adapted to engage a projection 178 on the set screw 179 to hold the yoke in either retracted or contacting position relative to the platen 147. At the beginning of the forward movement of the carriage the tripper 175 will strike a spring 181, Fig. 15, on the main frame and disengage the tripper from the projection 178 on the set screw 179, and the spring 186 will pull the yoke towards the platen to bring the feed roller against the platen, and feed a sheet. At the end of the forward or printing stroke of the carriage, the arm 174 on the feed roller yoke 157 will strike the spring pressed dog 180 on the main frame and shift the feed roller to retracted position. When the yoke is thus returned to retracted position, the spring 175' restores the tripper 175 to the left, Fig. 21, with its notch 177' in engagement with the projection 178 to lock the yoke and feed roller in retracted position. When the tripper is operated by the spring 181 during the forward stroke of the carriage, it will disengage the tripper from the projection 178 and permit the spring 186 to pull the yoke 156 so that the feed roller 30 will engage the platen 147.

The spring 181 is slidably arranged on the main frame so that the tripper arm may be operated to bring the feed roller in engaging position with the platen at any desired point. 35 When the feed roller is not contacting with the platen the sheet is fed and the spring 181 may be set at any position to determine when the feeding of the sheet will commence. In this manner the machine is adapted to print 40 from body forms of any desired length and from sheets of different size.

It is desired that safety means be provided to prevent the platen from operating and attaining printing position when a sheet is not fed so that the platen will not come in contact with the ribbon. The sheet safety means comprise a longitudinal plate 182 Figs. 19, 20 which is maintained in position by the pins 183 extending through diagonal longitudinal 50 slots 184 in the plate. A finger 185 is provided with a pair of slots 186, and is slidably maintained in position on the arm 187 fixed to the housing by the set screws 188 and 189. A bell crank 190 pivoted on the screw 189, and extending through one of the slots 186 has a bifurcated arm 191 Fig. 19 which engages a pin 192 on the finger 185. A link 193 connected to the arm 194 of the bell crank 190 and to the plate 182, moves the plate 182 during vertical movement of the finger 185. A spring 195 is connected to the plate 182 to normally urge the arm 194 of the bell crank 190 to the left, Fig. 19, so that the finger 185 is normally in down position. 65 The edge 196, Fig. 20, of the plate 182 is lo-

cated adjacent the paper feed slot 141 and is urged inwardly across the slot when the arm 185 is moved upwardly. The machine is designed to feed a sheet into printing position and the impression is made while the sheet is being fed during forward movement of the carriage. When a sheet is in proper position in the slot 141, and the carriage is brought to the end of its rearward stroke to initial position Fig. 26, the finger 185 will strike the arm 170 and tend to operate the sheet safety means. However, the spring 173 connected to the arm 170 does not offer sufficient tension to raise the arm 185, because the plate 182 will engage the sheet and set up resistance. During rearward movement of the carriage the shoulder 170' of the arm 170 will operate on the pin 169 to move the platen to printing position and the finger 185 will depress the arm 170, because of the resistance set up by the sheet, so that the shoulder 170' on the arm 170 will not engage the pin 169 to recede the platen during forward movement of the carriage. When there is no sheet in the slot 141, there will be no resistance on the plate 182 or finger 185 and the arm 170 will not be operated by the finger 185 but will operate the arm 168 to lower the platen into impression position as the pin 169 strikes the shoulder 170'. Upon forward movement of the carriage the pin 169 will strike the shoulder 170' and recede the platen.

A cross bar 197 Figs. 13 and 14 is provided with clips 198, which receive the plate 199 to which the two tapes 200 are connected. 100 These tapes pass around rollers 201, which are loosely mounted on the transverse shaft 202, pass around the rollers 203 at the opposite end of the frame, and are fastened to the pins 204 Fig. 16 on the bottom of the carriage. The rollers 203 are loosely mounted on yokes 205, on the transverse shaft 206 supported in the forward end of the main frame. Springs 207 secured to the yokes and to the main frame normally pull the yokes forward to provide the necessary tension on the tapes. Collars 208, Fig. 16, are arranged at the sides of the yokes and a set screw 209 is provided in each collar to prevent lateral movement 110 of the yokes and to permit adjustment thereof. The tapes carry the sheet away after it has been printed and deliver it to the sheet removing mechanism, where the sheet is carried and deposited in a drawer 210 slidably in the bottom of the frame. The sheet carrying mechanism comprises a sprocket 211 Fig. 13 which is fixed to the transverse shaft 202 and operates a roller 212 through the medium of a ratchet clutch (not shown) of common construction. A chain 213 trained around the sprocket and around the roller 212 is connected to a pin 214 on the carriage, so that when the carriage is moved the chain will move therewith and operate the ratchet. 120 A pair of rollers 215, Fig. 13 are arranged ad-

jacent the roller 212 and engage the chain to take up slack therein and maintain the chain in proper position. A roller 216 mounted on the arm 217 at the forward end of the main frame assists in taking up the slack in the chain and keeps it taut and prevents sagging. A belt 218 is supported by the rollers 219 and is operated by the roller 212' which is rigidly mounted on the shaft 202. During forward movement of the carriage the sprocket is disengaged from the roller 212' and the belt 218 remains stationary. When the carriage is moved rearwardly the sprocket is engaged with the roller 212' and operates the belt 218. The printed sheet is delivered by the tapes into the throat between the roller 212' and the belt 218 which carry the sheet away and deposit it in the drawer 210. Due to the different diameters of the sprocket 211 and the roller 212', the latter causes relatively fast movement of the belt 218 as compared with the movement of the tapes 200 so that the printed sheet is removed from the form at a relatively high rate of speed. An adjusting screw 218' is provided to take up any slack that may occur in the belt 218. The drawer is slidably mounted on a pair of longitudinal rods 221 Fig. 3, which are supported in the machine. Lugs 222 on the carriage Fig. 16 engage cushion stops 223 in the main frame.

The machine is also adapted to print consecutively from the body form alone and means are provided to throw out the cam lever 16 to prevent operation of the carrier plate 20 so that printing devices will not be fed to printing position. The transverse rod 13, Fig. 16, has a pin 224 thereon which travels in a slot 225 in the sleeve 226 in which the shaft 13 is supported. A lever 227 is pivoted to the bottom of the carriage at 228 and is connected to the sleeve 226 so that side movement of the lever 227 will move the sleeve to the left, Fig. 16, and rotate the shaft 13 to disengage the roller 14 from the groove 15 in the cam lever 16 so that the carriage may be operated without operating the carrier plate 20. Consecutive printing is usually for printing second sheets in which case no printing device is required and the carrier block 33 is removed and another block 229 Fig. 25 is substituted to fill the gap caused by the removal of the block 33.

The housing 5 of the carriage is pivotally connected to the lower part 4 by a pin 232, Fig. 15. A bolt 233, Fig. 22, is arranged in the housing on the side opposite the pin 232 and it is provided with projections 234 which are adapted to engage the projections 235 on the lower part to lock the two parts of the main frame together. A spring 236 normally holds the bolt 233 in locked position. Forward movement to the left, Fig. 22, of the bolt is limited by the shoulder 237 which engages the pin 238. A screw 239, Fig. 22, is

mounted in the yoke 157 and a flexible metal strip 240 is connected to the screw 239 and to the member 241 and engages the platen roller 147 to properly guide the sheet through printing position and onto the upper side of belts 200, Figs. 17 and 22. A spring member 242 is fastened to the yoke 156 by the screw 243 and bears against the member 240 so that the member 240 will constantly be in engagement with the platen roller. An operating handle 244 is connected to the front end of the carriage for operating the carriage.

The operation of the machine is as follows. The carriage is in initial operating position in Fig. 26, a sheet 128 is raised and dropped on the forward side of the baffle 130, Fig. 14, where it comes to rest on the ears 230 on the stripper plate 231. During the forward or printing movement of the carriage, the pin 169 will strike the shoulder 170" of the arm 170 and raise the platen from printing position if no paper is being fed. If paper is properly fed the finger 185 will depress the arm 170 and prevent the pin 169 from striking the shoulder 170" so the platen will remain in printing position. During continued movement of the carriage the tripper 175 will strike the spring 181 and move the stripper plate 231 to push the sheet off of the ears 230 and also release the arm 175 from the projection 178 which permits spring 166 to pull the feed roller 155 into contact with the platen 147 for feeding the sheet into impression position. At the end of the forward stroke of the carriage the arm 174 and the pin 169 on the arm 168 will strike the lug 180 to recede the platen and to release the feed roller from the platen. Upon rearward movement of the carriage the roller 14 will swing the cam lever 16 so that the printing device that has just been printed will be returned to pushed position in the feed frame and in the path of the dogs 49. Continued rearward movement of the carriage causes the lug 27 to strike the lug 26 and move the feed bar 24 so that the printing device which has just been printed will be carried to the chute 86, and the next succeeding printing device will be pushed from beneath the stack in the feed frame by the arms 31 and during the next printing stroke of the carriage this printing device will be carried by the carrier plate 20 into printing position before the carriage reaches the end of its forward stroke, Fig. 27.

The invention provides a machine of novel and compact construction which will print from a single body form, and from successively changing address forms, or will print consecutively from the body form alone as required. The machine is provided with simple parts for selecting certain printing devices to be printed and for preventing operation of the carriage when a printing device not select-

ed for printing is fed from the magazine. The platen is raised from impression position when a sheet is not fed, and the ribbon mechanism is adapted to be bodily reversed.

Changes may be made in the form, construction and arrangement of the parts without departing from the spirit of the invention, or sacrificing any of its advantages, and the right is hereby reserved to make all such changes as fairly fall within the scope of the following claims.

We claim:

1. A printing machine comprising a frame having a body form thereon, means alongside the frame for feeding address printing forms, means for laterally shifting an address form in its own plane from the line of feed into printing position adjacent the body form and for returning said address form in its own plane to the line of feed, a carriage movable across said printing form in printing position, and an impression platen carried by said carriage.
2. A printing machine comprising a frame having a body form thereon, a carriage movable back and forth over said body form, an impression platen carried by said carriage, means alongside the body form for feeding printing devices in their own plane in a direction parallel with the travel of the carriage, means for shifting laterally an address form in said plane from the line of feed into printing position adjacent the body form and for returning said address form in said plane to the line of feed.
3. A printing machine comprising a frame having a body form thereon, a carriage movable back and forth over said body form, an impression platen carried by said carriage, means alongside the body form and operated by the carriage for feeding printing devices in a direction parallel with the travel of the carriage, means for laterally shifting an address form from the line of feed into printing position adjacent the body form and for returning said address form in the same path to the line of feed.

4. A printing machine comprising a frame having a body form thereon, a carriage movable back and forth over said body form, an impression platen carried by said carriage, means alongside the frame for feeding printing devices in a direction parallel with the travel of the carriage, means operated by the carriage for shifting an address form from the line of feed into printing position adjacent the body form and for returning said address form to the line of feed.

5. A printing machine comprising a frame having a body form thereon, a carriage movable back and forth over said body form, an impression platen carried by said carriage, means alongside the frame for feeding printing devices in a direction parallel with the travel of the carriage, means for shifting an

address form from the line of feed into printing position adjacent the body form and for returning said address form to the line of feed, said feeding and shifting means being operated by the carriage.

6. A printing machine comprising a frame having a body form thereon, a carriage movable back and forth over said body form, an impression platen carried by said carriage, a magazine containing a stack of address forms, means for feeding the address forms one at a time from the stack and in a direction parallel with the travel of the carriage, and a carrier operating transversely of the frame and feeding means and adapted to receive an address form from the stack and carry it into printing position adjacent the body form and return said address form to its position in the line of feed.

7. A printing machine comprising a frame having a body form thereon, a carriage movable back and forth over said body form, an impression platen carried by said carriage, a magazine containing a stack of address forms, means for feeding the address forms one at a time from the stack and in a direction parallel with the travel of the carriage, and a carrier operated by the carriage transversely of the frame and feeding means and adapted to receive an address form from the stack and carry it into printing position adjacent the body form and return said address form to its position in the line of feed.

8. A printing machine comprising a frame having a body form thereon, a carriage movable back and forth over said body form, an impression platen carried by said carriage, a magazine containing a stack of address forms, means for feeding the address forms one at a time from the stack and intermittently in a direction parallel with the travel of the carriage and discharging said address forms from said feeding means, and a carrier for receiving the address form in the line of feed and carrying it transversely of the frame and feeding means into printing position adjacent the body form and for returning said address form to the line of feed.

9. A printing machine comprising a frame having a body form thereon, a carriage movable back and forth over said body form, an impression platen carried by said carriage, a magazine containing a stack of address forms, means for feeding the address forms one at a time from the stack and intermittently in a direction parallel with the travel of the carriage and discharging said address forms from said feeding means, and a carrier for receiving the address form in the line of feed and carrying it transversely of the frame and feeding means into printing position adjacent the body form and for returning said address form to the line of feed, said feeding means and carrier being operated by the carriage.

10. A printing machine comprising a frame having a body form thereon, a carriage movable back and forth over said body form, an impression platen carried by said carriage, means for feeding an address form alongside the body form in the direction of travel of the carriage, means for shifting said address form from the line of feed into printing position adjacent the body form and for returning said address form to the line of feed, said shifting means comprising a carrier, and a cam on the carriage for imparting a reciprocating movement to said carrier transversely of the body form and feeding means. 15
11. A printing machine comprising a frame having a body form thereon, a carriage movable back and forth over said body form, an impression platen carried by the carriage, means for feeding address forms alongside the body form, means for shifting certain address forms from the line of feed into printing position adjacent the body form and for returning said address forms to the line of feed, and automatic means for selecting the address forms to be shifted. 20
12. A printing machine comprising a frame having a body form thereon, a carriage movable back and forth over said body form, an impression platen carried by the carriage, means for feeding address forms alongside the body form, means for shifting certain address forms from the line of feed into printing position adjacent the body form and for returning said address form to the line of feed, and automatic means for selecting the address forms to be shifted and for locking the shifting means against address forms not selected for shifting. 25
13. A printing machine comprising a frame having a body form thereon, a carriage movable back and forth over said body form, an impression platen carried by the carriage, means for feeding address forms alongside the body form, means for shifting certain address forms from the line of feed into printing position adjacent the body form and for returning said address form to the line of feed, and automatic means for selecting the address forms to be shifted and for locking the shifting means against address forms not selected for shifting. 30
14. A printing machine comprising a frame having a body form thereon, a carriage movable back and forth over said body form, an impression platen carried by the carriage, means for feeding address forms alongside the body form, means for shifting certain address forms from the line of feed into printing position adjacent the body form and for returning said address form to the line of feed, and automatic means for selecting the address forms to be shifted and for locking the shifting means against address forms not selected for shifting. 35
15. A printing machine comprising a frame having a body form thereon, a carriage movable back and forth over said body form, an impression platen carried by the carriage, means for feeding address forms alongside the body form, means for shifting certain address forms from the line of feed into printing position adjacent the body form and for returning said address form to the line of feed, automatic means for selecting the address forms to be shifted and for locking the shifting means against address forms not selected for shifting, and for locking the feeding means against address forms not selected for shifting. 40
16. A printing machine comprising a frame having a body form thereon, a carriage movable back and forth over said body form, an impression platen carried by the carriage, means for feeding address forms alongside the body form, means for shifting certain address forms from the line of feed into printing position adjacent the body form and for returning said address form to the line of feed, automatic means for selecting the address forms to be shifted and for locking the shifting means against address forms not selected for shifting, and means for manually continuing the feed of said address forms not selected for shifting. 45
17. A printing machine comprising a frame having a body form thereon, a carriage movable back and forth over said body form, an impression platen carried by the carriage, means for feeding address forms alongside the body form, a carrier for laterally offsetting an address form from the line of feed to position adjacent the body form, and means for raising said carrier to align the address form into printing position. 50
18. A printing machine comprising a frame having a body form thereon, a carriage movable back and forth over said body form, an impression platen carried by the carriage, means for feeding address forms alongside the body form, a carrier for laterally offsetting an address form from the line of feed to position adjacent the body form and cam means for raising said carrier to align the address form into printing position. 55
19. A printing machine comprising a frame having a body form thereon, a carriage movable back and forth over said body form, an impression platen carried by said carriage, an ink ribbon supported in printing position, means for feeding address forms 60

alongside the body form and in a direction parallel with the travel of the carriage, means for laterally shifting an address form from the line of feed and beneath the ribbon to the line of carriage travel and for returning said address form to the line of feed, and means for raising the address form into printing position beneath the ribbon.

20. A printing machine comprising a frame having a body form thereon, a carriage movable back and forth over said body form, an impression platen carried by said carriage, a magazine at one side of the frame and containing a stack of address forms, and means operable during a cycle movement of the carriage for moving an address form from the stack in a line of feed, then laterally to printing position adjacent the body form and back to the line of feed, and then 20 onward in the line of feed to discharge position.

21. A printing machine comprising a frame having a body form, a magazine containing a stack of address forms, means for feeding said address forms from the magazine, means for selecting certain address forms to be printed, means for shifting out of the line of feed the address forms to be printed and for returning them to the line of feed, an impression platen on a carriage, and means for preventing the operation of said shifting means when an address device is not selected for printing.
